United States Patent Office.

A. E. ROBERTS, OF DES MOINES, IOWA.

Letters Patent No. 98,801, dated January 11, 1870.

IMPROVED SCHOOL-DESK.

The Schedule referred to in these Letters Patent and making part of the same.

To all whom it may concern:

Be it known that I, A. E. ROBERTS, of Des Moines, in the county of Polk, and in the State of Iowa, have invented certain new and useful Improvements in School-Desks; and do hereby declare that the following is a full, clear, and exact description thereof, reference being had to the accompanying drawings, and to the letters of reference marked thereon, making a part of this specification.

The nature of my invention consists in the construction of a "hinge," to be used in school-desks for folding the seat backward.

In order to enable others skilled in the art to which my invention appertains, to make and use the same, I will now proceed to describe its construction and operation, referring to the annexed drawings, in which—

Figure 1 is a side view, and

Figure 2, a vertical section of the whole hinge.

Figure 3 is a plan view of the seat-supporting bar, which forms the male part of the hinge, and

Figure 4 is a side view of an iron forming the inner side of the hinge.

A represents a portion of the iron frame of my school-desk.

Projecting forward of this iron frame, and supported by the front leg B of the same, is an irregular iron, C, which is cast solid with the frame A.

The upper part of this irregular iron C of the hinge is round, and made so for the convenience of the rib D, on the iron E, both of which support the slats or board for the seat, which seat may be let down nearly horizontal when required for a seat, and lifted to a perpendicular when not required.

The end of the iron E, which works in the hinge, and in fact forms a part of the same, is made flat,

with a lug, a, on each side, acting as a fulcrum, and these round lugs or pivots a a work in holes on or at a dead centre of the two lips, C C', which hold the iron E in its place, and support the seat when constructed.

The lip or side C' of the hinge is cast separate, and bolted to the iron frame A by the iron bolt b, which holds the entire hinge together.

The lower part of the side C' of the hinge is made so as to shoulder on the iron frame A, to keep it from turning.

The inside of both of the sides of the hinge is made hollow, to take in a blind leather or rubber washer, i i, as seen in fig. 2, to prevent friction, and to make the hinge noiseless.

The end of the iron E is made in such shape as to work easily in the hinge, and is shouldered at, or has bearings d and e to stop it from turning further than is desired for its proper use for a seat, and also from striking the back-board of the desk.

Having thus fully described my invention,

What I claim as new, and desire to secure by Letters Patent, is—

A hinge for school-desks, when constructed as described, by the end of the seat-supporting iron D, provided with journals, and fitting between a projection or lip, C, on the frame, and a removable lip, C', secured to the same, substantially as herein set forth.

In testimony that I claim the foregoing, I have hereunto set my hand, this 17th day of August, 1869.

A. E. ROBERTS.
